UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,400,075.

Specification of Letters Patent.

Patented Dec. 13, 1921.

Application filed August 11, 1917. Serial No. 185,705.

To all whom it may concern:

Be it known that I, CHARLES W. KECKLER, a citizen of the United States, residing at Newark, in the county of Essex and State of New Jersey, have invented certain new and useful Improvements in Telephone-Exchange Systems, of which the following is a full, clear, concise, and exact description.

This invention relates to telephone exchange systems, and more particularly to circuits and apparatus for selective party line signaling in such systems.

The principal object of the invention is to provide a system wherein the A operator may select and supply any desired signaling current or combinations thereof at a B position, by the same operations which she would employ in signaling a called party at the A exchange, and without the B operator being required to do anything beyond setting up the desired connection. This object is accomplished by the provision of means at the B position, responsive to the usual signaling current at the A position to connect a source of proper current to the line of the subscriber called to operate his particular party signal.

Another object of the invention is to provide a system wherein the usual signaling apparatus necessary for the operation of the party line signals of the subscribers associated with the A exchange is utilized to automatically apply signaling current from the usual apparatus necessary for the operation of the party line signals of subscribers associated with the B exchange to signal subscribers of the B exchange. To this end, means are provided at the B exchange responsive to the particular signaling current applied at the A exchange which operates to supply signaling current from apparatus at the B exchange adapted to actuate the signals allotted to particular stations of party lines associated with the B exchange corresponding to the party line station associated with the A exchange whose signal is operated by the particular current applied at the A position.

A further object of the invention is to provide a telephone system wherein an operator at one office can effect the selective operation of apparatus at a second office by and in accordance with the particular desired signaling current or combinations thereof selected at the first office from a plu-

rality of signaling currents of different characteristics available thereat. In accordance with this feature of the invention, a connecting circuit extends between the two offices and means are provided at the second office, and associated with this circuit, which is selectively operable by and in accordance with the particular desired signaling current selected and applied to said circuit at the first office from means at the first office supplying a plurality of signaling currents of different characteristics.

It often happens that a telephone subscriber desires connection with another subscriber who is on a party line associated with another exchange. In such a case it has heretofore been the general practice for an A operator at the exchange of the calling party to obtain the exchange name and telephone and party indication of the person desired in the usual manner. The A operator then communicates over an order wire circuit with a B operator at the exchange of the called party and the B operator on being told the line and party number of the subscriber desired informs the A operator the particular trunk to be used between the two exchanges and places the calling plug of this trunk into the jack of the line of the called subscriber. The A operator thereupon places the calling end of her cord or link circuit, already associated with the calling line, into the jack of the allotted trunk. If the party system be one having an individual jack for each of the parties on the line, the operator B is supposed to select the proper group of jacks and the particular jack therein individual to the desired party and to connect signaling current to such line. In systems using but a single jack per party line, the B operator, although relieved of having to select a particular jack of a group allotted to the different parties on that line, has heretofore been under the duty of selecting and applying the proper signaling current to operate the signal of the desired party. In both systems the responsibility of selecting the proper party is placed upon the B operator. Thus, while the A operator had complete control of the connection as soon as the calling party answers she had no direct way of determining whether the B operator connected to and signaled the proper party on the desired line.

With the present invention, which is applicable to party lines having but a single jack per line, the B operator is given only the line number of the desired party and so handles a party call in the same manner as a private line call. The duty of selecting and signaling the proper party devolves upon the A operator, who is thus in a position to directly ascertain if the proper key for the particular party desired was operated, without the aid of the B operator. The A operator, however, except for obtaining the trunk assignment from the B operator, handles the call in the same manner as if the multiple jack of the called party were directly available. The jack of the trunk assigned would correspond to the jack of the called party, so far as the A operator is concerned, and she would insert the calling end of the cord therein and operate the proper party key of the ringing key associated with the particular cord to supply signaling current in the same way as if signaling a party line subscriber associated with the A exchange and having his line jack located on the A operator's switchboard. The supervisory signals would operate in the same manner and indicate the same condition of connection, whether the call was a trunk or local call, and the connection would be supervised by the A operator in the same way in both cases.

Referring to the drawings, which illustrate embodiments of the invention, Figure 1 is a diagrammatic showing of circuits and apparatus for utilizing the invention in connection with a party line telephone system using biased signals; while Fig. 2 is a similar showing of the invention as applied to a line system using harmonic signals. The invention will be best understood from a description of the operation of the respective systems shown in the drawings.

In Fig. 1, the necessary circuits and apparatus of the invention, as applied to superimposed current signaling systems using biased signals, is indicated; the circuit and apparatus of the calling subscriber and that at the A operator's position being indicated to the left of the dotted line, and that at the B operator's position and at the called line being indicated to the right thereof.

The party at the calling substation 3 would signal the A operator, who would insert the answering end of a cord into the jack 4 of the calling party, and connect her operator's set (not shown) with the subscriber in the usual manner. The calling subscriber would give the exchange, number and party indication of the subscriber desired, the latter being connected to another exchange. The A operator would thereupon communicate with the B operator at the desired exchange over an order wire circuit (not shown), and give only the number of the called party. The B operator would test the jack 5 of the called

line and if idle would insert the plug 6 of an idle trunk extending from the A operator's position into jack 5 and notify the A operator of the number of the trunk which had been selected.

Upon the B operator plugging into the jack 5 a circuit is completed through the usual cut-off relay 7 of the called line to energize the relay 8 of the trunk at the B operator's position; this circuit extending from ground, winding of relay 7, sleeve connections of jack 5 and plug 6, conductor 9, and winding of relay 8 to grounded battery. Relay 8, pulling up, closes a circuit to light the signal lamp 10, this circuit extending from ground, lamp 10, right-hand armature and front contact of relay 8, conductor 11, inner armature and back contact of relay 12, conductor 13, back contact and armature of relay 14, to grounded battery. A circuit is also completed to operate a relay 15, which serves to temporarily open the cord circuit of the B position, and to prepare for the transmission of signaling current to the called line. This circuit extends from grounded battery, front contact and left-hand armature of relay 8, conductor 16, winding of relay 15, outer lower armature and back contact of relay 17, conductor 18, and back contact and armature of a slow operating relay 19 to ground. The relay 19 is both slow to pull up and slow to release for reasons to be hereinafter described.

The A operator would depress the proper party key associated with the cord in use at the time the calling subscriber gave her the number or while obtaining the trunk assignment from the B operator. A circuit is thus prepared and is completed on the A operator placing the plug 20 of her cord in the jack 21 of the assigned trunk to send signaling current over the calling end of the cord to actuate apparatus at the B position. Assume that the party key K', which corresponds to the party indication of the called subscriber, has been operated to disengage the center from the inner springs and to engage them with the outer ones. On the A operator placing the plug 20 in the jack 21 of the trunk to the B position a circuit is completed to operate relays 22 and 23, this circuit extending from ground, through resistance 24, sleeve connections of jack 21 and plug 20, conductor 25, winding of relay 22, conductor 26, winding of relay 23, and supervisory lamp 27 to grounded battery 28. It will be noted that this circuit is not completed until the plug 20 has been fully inserted and that the tip side of the operator's cord is normally open at the upper armature of relay 22. It is, therefore, impossible to have signaling current on the tip of the plug 20 during insertion thereof and any possibility of giving a false signal through the tip of the plug contacting with the sleeve spring of the jack 130

is thus avoided. Immediately on the A operator plugging into the jack 21, and the operation of relay 22, a circuit is completed to energize the relay 14 at the B position, this circuit extending from the positive side of battery 29, tip side of the A cord to the back contact and upper armature of relay 30 and upper armature and front contact of relay 22, tip connections of the plug 20 and jack 21, conductor 31, upper left-hand winding 32 of the repeating coil at the B position, conductor 33, both windings of relay 14, lower left-hand winding 34 of the repeating coil, conductor 35, ring connections of jack 21 and plug 20, ring side of A cord through the lower armature and back contact of relay 30, and winding of marginal relay 36 to the other side of battery 29. The relay 36 is so margined that it will not operate when 20 in series with both windings of relay 14, but will operate when the left-hand winding is removed from the circuit, as hereinafter explained. The operation of the relay 14 opens the circuit of the supervisory signal 10, 25 which is thus extinguished, and indicates to the B operator that the A operator has connected with the assigned trunk.

The keys K' and K² are arranged to operate with the tip side of the line in the 30 transmission of signaling current when either of them is operated at or subsequent to the operation of the relay 22, and in this event, a circuit is intermittently completed to operate relay 37 from battery 38, through 35 a constantly rotating interrupting device 39 arranged to synchronize with another constantly rotating interrupting device 40. The device 40 has two segments connected so as to impress negative superimposed signaling 40 current on the conductor 41 during a part of the revolution and to remove this signaling current and substitute direct current during the remainder of the revolution, the conductor 41 being connected with the negative 45 side of the battery 38 under this condition.

The application of battery current to the conductor 42 extending to the relay 37 coincides with the application of signaling current to the conductor 41, and if either of the 50 keys K' or K² is depressed, completes a circuit for the relay 37 at this time. The circuit for the operation of Key K' extends from grounded battery 38, interrupting device 39, conductor 42, contact 43 in its normal position, winding of relay 37, conductor 44, contact 45, now engaged with the lower armature of relay 22, conductor 46, inner and middle right-hand springs of key K⁴, inner and middle right-hand springs of key 55 K³, middle and inner right-hand springs of key K², and middle and outer right-hand springs of K' to ground. Relay 37 on pulling up completes a locking circuit for itself, 60 extending from grounded battery 47, lower armature of relay 37 and contact 43 in the

off-normal position, and thence over the remaining portion of the circuit previously traced, to the outer left-hand spring of key K', to ground. The operation of the lower armature of relay 37 operates contact 43 to disconnect it from conductor 42, leading through the interrupting device 39, to battery 38.

In the meantime, the operation of the relay 23 completed a circuit to operate relay 30, 75 this circuit extending from ground, front contact and armature of relay 23, resistance 48, conductor 49, armature and back contact of a slow actuated marginal relay 50, conductor 51, armature and back contact of relay 52, conductor 53, and winding of relay 30 to grounded battery. The key K' being operated, energization of relay 30 serves to connect positive superimposed current on the tip side of the cord and completes a circuit to 80 operate a biased relay P' at the B position; the relay P' being responsive to positive superimposed current and so connected as to operate only when such current is placed on the tip side of the A operator's cord. The 85 relay P² is responsive to negative superimposed current over the tip side of the line, while relays P³ and P⁴ respond respectively to positive and negative superimposed current over the ring side of the line. The circuit for the relay P' extends from grounded 90 alternating generator 54, through battery 55, having its positive side leading to a constantly rotating interrupting device 56 similar to the interrupting device 40, conductor 100 57, left-hand winding of relay 50, conductor 58, outer and middle left-hand springs of key K', inner and middle left-hand springs of Key K², conductor 59, front contact and upper armature of relay 37, conductor 60, 105 front contact and upper armature of relay 30, upper and front contact of relay 22, tip connections of plug 20 and jack 21, conductors 31 and 61, front contact and outer upper armature of relay 15, conductor 62, 110 and winding of relay P' to ground.

Relay P' serves as an electromagnetic switching means to complete a local operating circuit for a relay R', this circuit extending from grounded battery, front contact and left-hand armature of relay 8, conductor 63, armature and front contact of relay P', conductor 64, winding of relay R', conductors 65 and 66, and back contact and armature of relay 19, to ground. Relay 115 R' thereupon pulls up, forming a holding circuit for itself and shunting out the relay P', which then returns to its normal position. This holding circuit extends from grounded battery, front contact and left-hand armature of relay 8, conductors 63 and 67, winding of relay 12, conductor 69, left-hand armature, front contact and winding of relay R', conductors 65 and 66, and back contact and armature of relay 19, to ground. 120 130

The relays P^2 , P^3 and P^4 are associated with relays R^2 , R^3 and R^4 respectively and on operating energize their respective relays R^2 , R^3 or R^4 , as the case may be, to obtain 5 the proper selection of signaling current at the B position to operate the signal of the particular subscriber desired on the party line with which the plug 6 is connected.

In the meantime, the relay 12, being included in the holding circuit of relay R' , would have pulled up, closing at the outer armature a circuit to shunt out relay 14, to permit the armature thereof to fall off. This shunt circuit begins at conductor 31 10 and extends over conductor 61, front contact and outer upper armature of relay 15, conductor 62, conductor 85, front contact and outer armature of relay 12, conductors 86 and 87, to conductor 35. The armature of 15 relay 14 in falling off, closes a circuit to actuate a relay 88, this circuit extending from grounded battery, armature and back contact of relay 14, conductor 13, inner armature and front contact of relay 12, winding 20 of relay 88, conductors 89 and 66, and back contact and armature of relay 19, to ground. On the operation of relay 88, a shunt path is provided around the relay 12, which is thereby deenergized; this shunt path starting 25 at the junction of conductors 63 and 67 and extending over conductor 63 to the inner left-hand armature and front contact of relay 88, and conductor 90 to conductor 69. The relay 88, however, on pulling up, 30 completes a holding circuit for itself which is unaffected by the deenergization of relay 12, this circuit extending from grounded battery, front contact and left-hand armature of relay 8, conductor 63, inner left-hand 35 armature and right-hand armature and winding of relay 88, conductors 89 and 66 to back contact and armature of relay 19 to ground. The shunting out of relay 14 also permitted marginal relay 50 to operate, 40 thereby opening the shunt circuit about relay 52, which thereupon pulls up over a circuit from ground, front contact and armature of relay 23, resistance 48, conductor 99, winding of relay 52, conductor 53, and 45 winding of relay 30 to grounded battery. The energization of relay 52 completes a holding circuit therefor through its armature and front contact to grounded battery, and also shunts out the relay 30, whose 50 armatures thereupon fall off. The circuit by which signaling current at the A position is supplied to the A cord is thereby interrupted, while the connecting circuit through the A cord is completed through 55 the back contacts and armatures of relay 30. The circuit from battery 29 through the relay 14 at the B position is thus re-established to keep this relay energized; the relay 14 being so designed as to operate on 60 the superimposed signaling or battery cur-

rent associated with the interrupting devices 40 and 56 at the A station, as well as on current from battery 29. The supervisory relay 36 is included in this circuit but is so margined that it does not operate so long as it is in series with both windings of relay 14. 70

The operation of relay R' also alternately connects in circuit superimposed signaling current and a direct current source suitably arranged through interrupting devices substantially the same as those shown at the A position to supply the proper current combination to operate the signal of the called party and selected by the operation of the proper party key at the A position. For the relay R' this circuit extends from grounded alternating current generator 70 or battery 71, having a positive side intermittently extended to conductor 72 by the interrupting device 73, thence through the front contact and right-hand armature of relay R' , conductor 74, left-hand winding of relay 19, conductor 75, front contact and inner upper armature of relay 15, tip side 80 of B cord, and signaling relays 76, 77, 78 and 79 in parallel to conductor 80, thence to ring connections of jack 5 and plug 6, inner lower armature and front contact of relay 15, conductor 81, right-hand winding 90 of relay 19, conductor 82, right-hand armature and back contact of relay R^3 , left-hand armature and back contact of relay R^4 and conductor 83, to ground. The signaling relays 76 and 77 are biased so as to operate 100 only on positive superimposed current, and relays 78 and 79 only on negative superimposed current, so that relays 76 and 77 would be the only ones operated by the positive superimposed current in the present instance. These last mentioned relays close 105 circuits for their respective biased signals S' and S^2 , but signal S' is the only one of the two to respond to the positive superimposed current supplied at this time, the 110 circuit therefor extending from ground, alternating current generator 70, over the circuit just traced to the winding of relay 76, thence by conductor 84 and armature and front contact of relay 76 to grounded signal 115 S' . Relay 76 is thus locked up during the interval that superimposed signaling current is being supplied through the interrupting device 73. When the interrupting device 73 connects direct current battery 71 to the 120 conductor 72, the circuit through the relays of the signals is opened as the direct current will not pass the respective condensers present in the parallel circuit through the relays 76, 77, 78 and 79. On superimposed 125 signaling current again being supplied, the signaling circuit is again completed and the relay 76 again responds to complete the circuit to operate signal S' , which is again actuated during the ringing interval. 130

This intermittent operation continues until the subscriber thereat responds to the operation of signal S' by removing his receiver from the hook. This shunts out relay 76 and its condenser, and relay 76 falling off opens the circuit of signal S'. The relay 19 will not pull up on alternating current but will either on direct or on superimposed current, so that it would operate on the completion of the direct current circuit completed on shunting out of relay 76 with its condenser. The relay 19 after pulling up will hold up, however, on superimposed signaling current. The relay 19 is made slow to operate to prevent any momentary surge of direct current operating it prematurely, but the interrupting device 73 supplies direct current from the battery 71 a sufficient length of time to enable it to pull up at this time. The operation of relay 19 removes the shunt path around relay 17, which is then energized over a circuit extending from grounded battery, front contact and left-hand armature of relay 8, conductor 16, winding of relay 15, and lower winding of relay 17, to ground. The relay 15 is shunted out by the operation of relay 17 and disconnects signaling current from the B cord.

The lower armature of relay 17 pulling up, the circuit through the relays R' and 88, which are in parallel, is momentarily opened. The armature of relay 19 being pulled up at this time, thereby permits the relays R' and 88 to return to normal position. The falling off of relay R' opens a circuit through relay 19; but this relay is made slow to release in order to give relay 17 time to pull up and complete a holding circuit extending from grounded battery, front contact and left-hand armature of relay 8, conductor 16, front contact and outer lower armature of relay 17, and lower winding of relay 17 to ground. The relay 19 is also made slow to release in order to provide sufficient time for relays R' and 88 to fall off before the ground connection is again established at the armature and back contact of relay 19.

Relay 17 in pulling up completes the usual talking circuit through the calling end of the B cord and operates a relay 98 therein, which shunts out the left-hand winding of relay 14, this shunt beginning at conductor 33 and extending over conductors 91 and 92, armature and front contact of relay 98, conductor 93 to the junction of the two windings of relay 14 and through the right-hand winding thereof to winding 34 of the repeating coil. A shunt circuit for the alternating telephone currents incident to speech transmission is also provided about both windings of the relay 14, this circuit beginning at conductor 33 and extending over conductor 91, front contact and inner lower armature of relay 17, conductor 94 and condenser 95 to the

junction of the right-hand winding of relay 65 14, to the winding 34 of the repeating coil.

On the left-hand winding of relay 14 being shunted out of the direct current circuit through battery 29, relay 36 at the A position operated to supply battery 68 to keep 70 relay 23 energized, but providing a low resistance path through the armature and front contact of relay 36 to ground to shunt out the supervisory signal 27. Signal 27 will thus be extinguished and thereby indicate to 75 the A operator that the calling party has responded.

Conversation can now take place over the usual talking circuit, in which the A operator's cord provides a link circuit between 80 the line of the calling subscriber and the trunk to the B operator, and on completion, the parties will hang up their receivers in the usual manner. The circuit through the relay 98 is thereby opened and the shunt 85 about the left-hand winding of relay 14 removed, whereupon the left-hand winding thereof is again included in the circuit of the A cord through the relay 36, which is so margined as to fall off under these conditions. 90 The shunt circuit about the lamp 27 is thus removed and the lamp 27 again lights up brightly to indicate that the called party has completed conversation. The A operator on receiving a like indication from the 95 supervisory signal (not shown) associated with the answering end of her cord, will know that disconnection is desired and accordingly pull out the plugs of her cord. This breaks the circuit through the relays 100 22 and 23 and also opens the circuit through the relay 36. These relays fall off, the relay 23 on so doing opens the circuit of relay 52, which thus falls off. Inasmuch as relay 50 was deenergized on the release of relay 30, 105 the apparatus at the A position is again in normal condition ready for subsequent calls.

When the A operator disengages the plug 20 from the jack 21, the circuit of relay 14 at the B position is opened, whereupon this 110 relay returns to normal, closing a circuit from grounded battery, armature and back contact of relay 14, conductor 13, inner right-hand armature and back contact of relay 12, conductor 11, front contact and 115 right-hand armature of relay 8, through signal lamp 10 to ground, thereby lighting the lamp and indicating to the B operator that disconnection is desired. The B operator thereupon pulls up the plug 6 from 120 the jack 5 of the called line, opening the circuit of relay 8 and cut-off relay 7 of the party line. The relay 8, falling off, breaks the holding circuit of relay 17, which thereupon drops back, restoring the apparatus 125 to normal condition ready for subsequent use.

Should the signal 27 remain lighted for an

unreasonably long interval after the A operator has signaled the called party, it would indicate that the latter had not responded, in which event the A operator would so inform the calling subscriber and withdraw the plug 20 from the jack 21. The relay 14 would be deenergized thereby and complete a circuit from grounded battery, armature and back contact of relay 14, conductor 13, 5 inner armature and back contact of relay 12, conductor 96, outer left-hand armature and front contact of relay 88, conductor 97, and upper winding of relay 17 to ground. The relay 17 will thereupon pull up and shunt out relay 15 and also complete the holding circuit, previously described, through the lower winding of relay 17. The relay 15, falling off, would open the signaling circuit, while deenergization of 10 relay 14 would light the signal lamp 10 to indicate disconnection was desired. The B operator would then withdraw the plug 6, opening the circuit of relay 8 and of cut-off relay 7, and relay 8 falling off opens a holding circuit through the lower winding of relay 17 and also the circuit of relays R' 15 and 88, at the left-hand armature of relay 8. Relays 17, R' and 88 thereupon drop off, restoring the apparatus to normal condition.

In Fig. 2, diagrammatically illustrating an embodiment of the invention as applied to a party line trunk system having harmonic signals, the substation of the calling subscriber is represented at 103. The subscriber's line terminates in a jack 104, located at an answering or A operator's position, and on receipt of the calling subscriber's signal (not shown) an A operator at that exchange would insert the answering plug 105 of an idle cord circuit into the jack 104 and connect her operator's set (not shown) with the subscriber in the usual manner. On receipt of a party number on another exchange, the A operator gives only the line indication of the called party to the B operator at the desired exchange. The B operator tests the called line and on finding it idle will insert the calling end 106 40 of an idle trunk extending between the two exchanges into the jack 107 of the called line, and at the same time inform the A operator of the number of the trunk assigned for the call. The other end of the 45 trunk terminates in a jack 108 at one or more A operators' positions at the A exchange.

The engagement of the plug 106 in the jack 107 completes a circuit through the 50 usual cut-off relay 109 of the called line and also through a relay 110, controlling the circuit of a guard and disconnect signal lamp 111 at the B position. This circuit extends from ground, winding of relay 109, sleeve 55 connections of jack 107 and plug 106, wind-

ing of relay 110 to grounded battery. The relay 110 pulling up closes a circuit to light the signal 111; this circuit extending from ground, signal 111, right-hand armature and front contact of relay 110, conductor 113, 70 back contact and inner armature of relay 114, conductor 115, and back contact and armature relay 116, to grounded battery. Another circuit is also closed to operate a relay 117 to prepare the calling end of the 75 trunk for the application of signaling current from the B position, this circuit extending from grounded battery, front contact and left-hand armature of relay 110, conductor 118, winding of relay 117, conductor 119, lower armature and back contact of relay 120, conductor 121 and back contact and armature of relay 122 to ground. A path also extends from the conductor 119, 80 through the lower winding of relay 120, to ground, but relay 120 does not operate at this time, due to the low resistance of the path to ground through the armature and back contact of relay 122.

The A operator on receiving the trunk assignment from the B operator will connect the calling plug 123 of her cord circuit with the jack 124 of the assigned trunk. Relay 125 at the A position is thereby operated over a circuit extending from grounded battery, winding of relay 125, conductor 126, sleeve connections of plug 123 and jack 124, and resistance 127 to ground. The operation of relay 125 lights a supervisory lamp 195, associated with the calling end of the 90 95 100 A cord; this circuit extending from grounded battery, the right-hand armature and front contact of relay 125, conductor 197, lamp 195, conductor 198, back contact and armature of relay 128 to ground. The relay 128 is so marginated that it will not pull up in series with both windings of relay 116, 105 but will operate on the shunting out of the lower winding of the latter relay, for a purpose hereinafter described.

Another circuit is also completed on the connection of the plug 123 and jack 124 to operate the relay 116 at the B position, this circuit extending from grounded battery, left-hand winding of relay 128, conductors 115 129 and 130, back contact and armature of relay 131, ring connections of plug 123 and jack 124, conductor 132, winding 133 of repeating coil at the B position, conductor 134, both windings of relay 116, conductor 135, winding 136 of the repeating coil, conductor 137, tip connections of the jack 124 and plug 123, conductor 138, armature and back contact of relay 131, conductor 139 and right-hand winding of relay 128, to ground. 125 The operation of relay 116 breaks the circuit of signal lamp 11 at the B position, extinguishing it and indicating to the B operator that connection has been made to the assigned trunk. The relay 128 did not op- 130

erate at this time and accordingly the signal 195 will remain energized until the called party responds, effecting the shunting out of lower winding of relay 116 and operation 5 of relay 128, in a manner to be later explained.

The relay 125, on operating, energizes relay 131 over a circuit extending from 10 grounded battery, left-hand armature and front contact of relay 125, conductor 140, winding of relay 131, conductor 141, armature and back contact of relay 142, conductor 143, and armature and back contact of relay 144, to ground. The relay 144 is 15 made slow to operate so that momentary surges of current will not effect its operation, and is also so margined that it will not operate unless the relay 116 at the B position is shunted out from its operating circuit. 20

The A operator would now operate one of the party line calling keys C', C², C³ or C⁴, associated with the A cord used, corresponding 25 to the particular party called. The keys C', C², C³ and C⁴ control the intermittent application of alternating signaling current and direct current, the alternating current generator respectively associated with each 30 key providing current of a particular frequency, depending on the particular party on the line; each station on a party line having a distinct frequency. In the present case the generator 145, associated with key C', has a frequency of 16 $\frac{2}{3}$ cycles per 35 second, while similar generators (not shown) are associated with keys C², C³ and C⁴ in the same manner and have frequencies respectively of 33 $\frac{1}{3}$, 50 and 66 $\frac{2}{3}$ cycles per second. A continuously rotating interrupting 40 device 146, provided for each of the generators has two segments insulated from each other, one segment being connected with the generator 145 and the other with a source of direct current 147 so that alternating 45 current and direct current will be alternately supplied to the conductor 148. Assume that the key C', corresponding to the called party, has been operated and that relay 131 has pulled up, as previously explained. 50 Under these conditions alternating signaling current from the generator 145 and direct current from the battery 147 are alternately connected to the conductor 148; the signaling circuit extending from grounded generator 145, interrupting device 146, conductor 148, outer and middle 55 upper spring of key C', conductor 149, winding of relay 144, conductor 150, front contact and upper armature of relay 131, conductor 138, tip connections of plug 123 and jack 124, conductors 137 and 151, condenser 152, winding of harmonic relay H', conductors 153 and 175, inner lower armature and front contact of relay 117, conductors 154 and 132, ring connections of jack 60

124 and plug 123, lower armature and front contact of relay 131, conductor 155, middle and outer lower springs of key C' and conductor 156, to ground. The relay H' is tuned to respond only to alternating current of a frequency allotted to key C', in the present case 16 $\frac{2}{3}$ cycles per second, while relays H², H³ and H⁴ are tuned to respond only to the frequencies allotted to their respective keys C², C³ and C⁴. Current may, 70 therefore, pass in parallel through the windings of all of the harmonic relays, but only the one tuned to the particular frequency will be operated. The relay 116 is made so as to hold up over either superimposed 75 signaling current of any of the frequencies used in the system, or on direct current and is, therefore, energized at this time over a circuit from conductor 137, through winding 136 of the repeater coil, conductor 135, 80 both windings of relay 116, conductor 134, and winding 133 of the repeating coil to conductor 132. 85

The operation of relay H' completes an energizing circuit for a relay G' associated therewith, this circuit extending from grounded battery, front contact and left-hand armature of relay 110, conductors 157 and 158, armature and front contact of relay H', conductor 159, winding of relay G', conductors 160 and 161 and back contact and armature of relay 122 to ground. Similar relays G², G³ and G⁴ are associated respectively with the relays H², H³ and H⁴ and when operated serve to close a circuit 90 to supply signaling current having the proper characteristics to actuate the particular party signaled with which it is designed to coöperate. In the present case, the party signaling devices B', B², B³ and 95 B⁴ are harmonic ringers, each tuned to respond only to a distinctive frequency; the frequencies indicated on the drawing being the same as those employed at the A position, although obviously other frequency 100 generators and signals could be used at the B position, as could also direct or superimposed current signaling generators with appropriate party signals to coöperate therewith, if desired. 110

In the present case, operation of relay G' completes a holding circuit, extending from grounded battery, front contact and left-hand armature of relay 110, conductors 157 and 162, winding of relay 114, conductor 120 163, left-hand armature, front contact and winding of relay G', conductors 160 and 161, and back contact and armature of relay 122 to ground, and also results in the operation of relay 114. An alternating 125 generator having a certain frequency depending on the particular party signal with which it coöperates is associated respectively with each of relay G', G², G³ and G⁴, as is also an interrupting device in the 130

source of direct current supply operated in the same manner as in generator 145, interrupter 146, and battery 147 at the A operator's position. Only the generator 164, interrupter 165 and the direct current battery 166 associated with the relay G' are shown, and on the relay G' pulling up, alternating signaling current from generator 164 is furnished at regular intervals through 10 a circuit extending from grounded generator 164, interrupting device 165, conductor 167, front contact and right-hand armature of relay G', conductor 168, winding of relay 122, conductor 169, front contact and 15 upper armature of relay 117, tip connections of plug 106 and jack 107, conductor 170, thence in parallel through the condensers 171 and windings of the signals B', B², B³ and B⁴ at the different substations in the 20 party line, to conductor 172, through ring connections of jack 107 and plug 106, outer lower armature and front contact of relay 117 to ground. The signals B², B³ and B⁴ are not operated, however, as the harmonic 25 signal B' is the only one tuned to respond to the particular frequency of the generator 164, associated with relay G'. No direct current circuit is completed from battery 166 at this time, due to the condensers 30 171 in the circuit just traced, while the relay 122 is not operative on alternating current.

The operation of relay 114 results in the preparation for a circuit through its inner armature and front contact for a relay 173, 35 the latter circuit being opened, however, at the armature and back contact of the relay 116 until the latter falls off on short-circuiting thereof through the engagement of the outer armature of relay 114 with its 40 front contact; this short circuit extending from conductor 137, by conductor 151, front contact and outer armature of relay 114, conductors 174 and 175, inner lower armature and front contact of relay 117, and conductor 154 to conductor 132. On relay 116 falling off, relay 173 operates, the circuit therefor extending from grounded battery, armature and back contact of relay 116, conductor 115, inner armature and front 45 contact of relay 114, conductor 176, winding of relay 173, conductors 180 and 161 and back contact and armature of relay 122 to ground. Relay 173 operating, short-circuits relay 114 by a path beginning at conductor 50 162 and extending over conductors 158 and 177, inner left-hand armature and front contact of relay 173 and conductor 178 to conductor 163. A holding circuit is also provided, extending from grounded battery, 55 front contact and left-hand armature of relay 110, conductors 157, 158 and 177, inner left-hand armature, right-hand armature, front contact and winding of relay 173, conductors 180 and 161, and back contact 60 and armature of relay 122, to ground.

The short-circuiting of relay 116 permitted the marginal relay 144 at the A position to operate, thereby opening the low resistance path about the relay 142 at the armature and back contact of the former, 70 whereupon the latter pulls up over a circuit extending from grounded battery, armature and front contact of relay 125, conductor 140, winding of relay 131, conductor 141, and winding of relay 142 to ground. 75 The engagement of the armature of relay 142 with its front contact provides a holding circuit therefor from grounded battery, armature and front contact of relay 125, conductor 181, front contact, armature and 80 winding of relay 142, to ground, and shunts out relay 131, which thereupon falls off. This opens the signaling circuit and thereby deenergizes relay 144.

In the meantime, on relay 144 being deenergized at the B position, the relay 116 is operated over the circuit previously traced through relay 128, this circuit having been reestablished on deenergization of relay 131 and the removal of the shunt circuit about 90 relay 116 on the retraction of the armature of relay 114.

Intermittent signaling current will be automatically supplied to the called line and intermittently operate the signal of the desired party until he responds or the A operator abandons the call. Assume that the party called responds and removes his receiver in the usual manner. The winding of signal B' is thereby shunted out by the 95 relatively low resistance path through the subscriber's set extending from conductors 170 through the transmitter, switchhook and primary of the induction coil 182, to conductor 172. This path also permits passage 100 of direct current from the battery 166 should the hook be removed during a non-signaling interval. On shunting out the winding of signal B', relay 122 will operate, removing the low resistance path heretofore present to shunt out the lower winding of relay 110. This relay is thereby operated by a 105 circuit extending from grounded battery, front contact and left-hand armature of relay 110, conductor 118, winding of relay 117, conductor 119, winding of relay 120, to ground. Relay 120 thereupon pulls up, completing a holding circuit from grounded battery, front contact and left-hand armature of relay 110, conductor 183, front contact, lower armature and lower winding of relay 120, to ground. Relay 117 is thereby shunted out and allows its armatures to drop back, breaking the signaling circuit through the relay 122. Relay 120 in 110 operating opens the circuit of relays G' and 115 173 which accordingly release. Relay 122 is made slow to release to insure the completion of the holding circuit for relay 120 and the release of relays G' and 173 before 120 130

the ground connection is again established at the armature and back contact of the relay 122.

A talking circuit, through the calling end of the B trunk is established by the energization of relay 120 and the falling off of relay 117, this circuit extending from battery 184, winding 185 of repeating coil, conductor 186, front contact and upper armature of relay 120, conductor 187, back contact and upper armature of relay 117, tip connections of plug 106 and jack 107, conductor 170, transmitter, hook switch and primary of the induction coil 182 at the called station, conductor 172, ring connections of plug 106 and jack 107, conductor 188, outer lower armature and back contact of relay 117, conductor 189, winding of relay 190, and winding 191 of the repeating coil to the other side of battery 184. The operation of relay 190 shunts out the lower winding of relay 116, which is of relatively high resistance, this shunt extending from conductor 134, over conductor 192, front contact and armature of relay 190 and conductor 193 to the junction of the upper and lower windings of relay 116.

The relay 128 controls a supervisory signal 195 at the calling end of the A operator's cord circuit and the shunting out of the lower winding of relay 116, permitting the relay 128 to pull up, opening the circuit previously traced for the signal 195 at the armature and back contact of relay 128. Signal 195 is thereby extinguished, indicating to the A operator that the called party has responded. The relay 116 remains energized on current through the upper winding and conversation takes place between the subscribers in the usual manner, the A operator's cord serving as a link circuit between the calling subscriber and the trunk circuit. On completion, the subscribers hang up their receivers and the circuit through the relay 190 is opened at the called station and thereupon falls back, removing the shunt about the lower winding of relay 116. Relay 128 will not hold up in circuit with both windings of relay 116 and thereupon falls back, completing the circuit of signal 195, which, lighting up, indicates that disconnection is desired. The A operator would thereupon remove the plug 123 from the jack 124, opening the circuit of relay 125, which on releasing breaks the holding circuit of relay 142, which then returns to normal position. Similar signals (not shown) will be displayed at the answering end of the cord, and the A operator will remove the plug 105 from the jack 104, thus restoring the apparatus at the A position to normal.

Relay 116 at the B position falls off on withdrawal of the plug 123, and its armature

at its back contact completes a circuit to 65 light up signal lamp 111, thus indicating to the B operator that the A operator has disconnected from the trunk. The B operator then disengages plug 106 from the jack 107, breaking the circuit of relay 110 and 70 of cut-off relay 109. Relay 110, releasing, opens a circuit to extinguish lamp 111, and also opens the holding circuit of relay 120, which, falling back, restores the apparatus of the B position to normal condition ready 75 for subsequent use.

Should the A operator disconnect while the called party is still being signaled by current from the apparatus of the B position, she would withdraw plug 123 in the 80 usual manner, whereupon the apparatus at the A position would be restored to normal, as previously outlined. The relay 116 of B position would drop off and light the disconnect signal 111, as before explained, and also 85 complete an energizing circuit for relay 120, extending from grounded battery, armature and back contact of relay 116, conductor 115, inner armature and back contact of relay 114, conductor 195, outer left-hand armature 90 and front contact of relay 173, conductor 196, and upper winding of relay 120 to ground. Relay 120 thereupon pulls up, completing a holding circuit through its lower winding and shunting out relay 117, which 95 falls off, opening the signaling circuit. The circuit extending in parallel through relays G' and 173 is maintained until the B operator disengages the plug 106 from the jack 107, whereupon relay 110 falls off, opening 100 the circuit through relays G' and 173, which thereupon return to normal position and also open the circuit of the signal 111, thereby extinguishing the latter and restoring the apparatus of the B position to normal condition. The cut-off relay 109 of the called line also falls off on disengagement with the plug 106 and completes the restoration of the 105 entire system to normal condition.

What is claimed is:

1. A telephone exchange system comprising a trunk circuit extending between a first and second central office, means at said first office to supply a plurality of signaling currents of different characteristics, means at 115 said second office to supply a plurality of signaling currents of different characteristics, a link circuit at said first office adapted to connect with said trunk circuit, means at said first office to connect any desired one 120 of said signaling currents at said first office with said link circuit, means associated with said trunk circuit and operated by the particular signaling current connected to said link circuit to automatically connect a particular current from said current supply means at said second office with said trunk circuit, and means to disconnect signaling 125

current at said first office from said link circuit on signaling current at said second office being supplied to said trunk circuit.

2. A telephone exchange system comprising a trunk circuit extending between a first and a second central office, a source of signaling current at said first office adapted to provide a plurality of currents of different characteristics, a link circuit at said first office adapted to connect with said trunk circuit, a source of signaling current at said second office adapted to provide a plurality of currents of different characteristics, means to connect any desired one of said currents at said first office with said link circuit, means associated with said trunk circuit and responsive to signaling current at said first office connected with said link circuit to connect a particular current at said second office with said trunk circuit, and means operated on connection of a particular current at said second office with said trunk circuit to automatically disconnect signaling current at said first office from said link circuit.
- 25 3. A telephone exchange system comprising a trunk circuit extending between a first and a second central office, a source of signaling current at said first office adapted to provide a plurality of currents of different characteristics, a link circuit at said first office adapted to connect with said trunk circuit, a source of signaling current at said second office adapted to provide a plurality of currents of different characteristics, means to select and connect any desired one of said currents at said first office to said link circuit, means associated with said trunk circuit and responsive to signaling current at said first office connected with said link circuit to connect a particular current at said

second office with said trunk circuit, and means operated on connection of a particular current at said second office with said trunk circuit to automatically disconnect the signaling current selected at said first office from said link circuit.

4. A telephone exchange system comprising a trunk circuit extending between a first and a second central office, a plurality of sources of signaling currents at said first office to provide signaling currents of different characteristics, a plurality of sources of signaling current at said second office to provide signaling currents of different characteristics, a link circuit at said first office adapted to connect with said trunk circuit, means at said first office to select a particular signaling current from said plurality of sources thereof, means associated with said trunk circuit to connect a particular one of said currents at said second office with said trunk circuit, the particular circuit connected depending upon the particular current at said first office connected with said link circuit, a called subscriber's line adapted to be associated with said trunk circuit, signals associated with said line and each responsive to a different one of said signaling currents at said second office, means to disconnect signaling current at said second office from said trunk circuit on the called subscriber responding, and means to disconnect signaling current at said second office from said trunk circuit on disconnection of said trunk and link circuits prior to response by said called subscriber.

In witness whereof I hereunto subscribe my name this 7th day of August A. D. 1917.

CHARLES W. KECKLER.
